CLAIM

The ornamental design for a paper clip, as shown and described.

DESCRIPTION

FIG. 1 is a front view of a paper clip showing my new design, which has been broken away for the purpose of indicating indeterminate length;

FIG. 2 is a rear view thereof;

FIG. 3 is a top plan view thereof;

FIG. 4 is a bottom plan view thereof;

FIG. 5 is a left side view thereof, the right side view being symmetrical to the left side view;

FIG. 6 is a magnified cross sectional view taken along line 6—6 in FIG. 4;

FIG. 7 is a cross sectional view taken along line 7—7 in FIG. 4;

FIG. 8 is a cross sectional view taken along line 8—8 in FIG. 4;

FIG. 9 is a front view of a paper clip showing a second embodiment of my design of FIG. 1, which has been broken away for the purpose of indicating indeterminate length;

FIG. 10 is a rear view of FIG. 9;

FIG. 11 is a top plan view of FIG. 9;

FIG. 12 is a bottom plan view of FIG. 9;

FIG. 13 is a left side view of FIG. 9, the right side view being symmetrical to the left side view;

FIG. 14 is a magnified cross sectional view taken along line 14—14 in FIG. 12;

FIG. 15 is a magnified cross sectional view taken along line 15—15 in FIG. 12;

FIG. 16 is a cross sectional view taken along line 16—16 in FIG. 12;

FIG. 17 is a cross sectional view taken along line 17—17 in FIG. 12; and,

FIG. 18 is a perspective view of the embodiment of FIG. 9, showing the complete article.
